UNITED STATES PATENT OFFICE.

CHARLES P. VAN GUNDY, OF CATONSVILLE, MARYLAND, ASSIGNOR TO KENNICOTT WATER-SOFTENER COMPANY, OF CHICAGO, ILLINOIS, A CORPORATION OF ILLINOIS.

WATER-PURIFYING APPARATUS.

No. 897,940.

Specification of Letters Patent.

Patented Sept. 8, 1908.

Application filed July 16, 1907. Serial No. 384,011.

To all whom it may concern:

Be it known that I, CHARLES P. VAN GUNDY, a citizen of the United States, residing at Catonsville, in the county of Baltimore and State of Maryland, have invented 5 certain new and useful Improvements in Water-Purifying Apparatus, of which the following is a specification.

My invention relates to water purifying 10 apparatus of the type wherein a determinate quantity of chemical is introduced into the water so that the impurities therein are precipitated or neutralized according to the result desired and chemicals used.

15 The invention consists in an improved device whereby the amount of chemical introduced is varied according to the variations in the water supply.

My invention will be understood from the 20 following description taken in connection with the accompanying drawing in which similar reference characters indicate the same parts in the several figures of drawing and wherein

25 Figure 1, is a central vertical section showing my improved apparatus, mounted on the top of a settling tank; Fig. 2, is an enlarged end view of the adjustable outflow opening of the water reservoir; Fig. 3, is a 30 similar view of the tilting chemical feed box.

1^a designates a settling tank equipped in any suitable manner with flushing valves, filter and overflow and having in the present instance a central pipe 2^a therein which may 35 have suitable openings into the tank in the lower part thereof (not shown). The tank 1^a may have overflow 3^a and a filter 4^a of excelsior or the like. A suitable perforated baffle 5^a and a conical funnel 6^a may be provided at the top of said pipe 2^a for the admission 40 of water thereto. Supported over the top of the tank 1^a and securely held on each side of the central pipe 2^a are I-beams 2^b. The water supply pipe 7^a, delivers into 45 a reservoir 8^a, said reservoir being mounted on the I-beams so that its overflow or open end overhangs as shown the funnel 6^a at the upper end of pipe 2^a. A suitable vertical slot 9^a is provided at the overflow end of the 50 reservoir 8^a, the opening or width of the slot being adjustable and a preferred means for effecting such an adjustment (see Fig. 2) is to have an adjustable plate 9^b adapted to

have its position regulated by suitable backing screws 9^c which screws may be threaded 55 through a rib 9^d on the reservoir.

11^a is a tilting chemical feed box or holder which is suitably pivoted at 10^a to a cross piece 10^b supported on the I-beams 2^b and so arranged that its open end also overhangs 60 the outer edge of funnel 6^a. 10^c is a cross piece also supported on the I-beams 2^b and which acts as a stop for the tilting box 11^a in its lowest or horizontal position. This tilting chemical box has an opening or slot 12^a 65 in its end overhanging the funnel 6^a the arrangement being such that upon the tilting of the box 11^a, the contents thereof are emptied more or less rapidly according to the amount of tilting, through the slot 12^a into 70 the funnel 6^a and central pipe 2^a. This slot 12^a is preferably made adjustable as shown in Fig. 3, and consists of similar means as that for the reservoir in being provided with an adjustable plate 13^a adapted to have its 75 position regulated by suitable locking screws 14^a which screws may be threaded through a rib 15^a on the box. Another opening or slot 16^a is formed in the end of the chemical box 11^a opposite the slot 12^a for the purpose hereinafter explained.

Pivotedly supported at 17^a upon a suitable standard 17^b is a lever 18^a, said lever having a pivoted connection at 19^a at its remote end to the rod 20^a of a float 20^b. Said float may 85 be guided in a perforated cylinder 21^a suitably arranged in the reservoir 8^a. The lever 18^a has a connection at 22^a with the tilting chemical box 11^a at a point opposite the pivot 10^a or approximately so. A chemical feed 90 pipe 24^a is arranged to deliver into the chemical box 11^a. By a forcing device (not shown) or other means a constant flow of chemical is fed through the pipe 24^a somewhat in excess of what is normally required for treating 95 the water as supplied by the pipe 7^a. A chemical return pipe 23^a, which may have a funnel at its top is arranged directly underneath the opening or slot 16^a.

The operation of the device will be readily 100 understood from the foregoing description. When the pipe 7^a delivers a larger quantity of water than usual, the water level in the reservoir 8^a rises thereby lifting the float 20^a. This float by the connections 19^a and 22^a with 105 the chemical box 11^a will cause said box to

be tilted to a greater extent, thus emptying a correspondingly larger proportion of the chemical therein into the funnel 6^a to mix with the water from the reservoir 8^a to be purified and permitting a smaller proportion of chemical to return by the opening or slot 16^a and pipe 23^a.

When the volume of water supplied by pipe 7^a falls below normal the reverse operation 10 takes place, the box 11^a assuming more nearly a horizontal position and hence a larger proportion of chemical will be discharged by slot or opening 16^a into the return pipe 23^a and a smaller amount will be added to the 15 water flowing into funnel 6^a.

The adjustability of the openings or slots 12^a and 9^a respectively in the chemical box 11^a and reservoir 8^a, enables me to change within wide limits, or preserve a predetermined ratio between the water and chemical 20 fed thereto.

The lever 18^a may be provided with a suitable counterweight 25^a, if desired, to facilitate tilting of the box 11^a. The perforate 25 cylinder 21^a serves as a guide for the float 20^a and also prevents too sudden fluctuations of the float by throttling the ingress of water thereto.

What I claim as new and desire to secure 30 by Letters Patent is as follows:—

1. A water purifying apparatus comprising a reservoir having an outlet, means for feeding water to said reservoir, a tilting chemical feed box having an outlet, means 35 connected to the chemical feed box and controlled by the volume of water in said reservoir for variably tilting said chemical feed box and automatically varying the outflow of chemical from said feed box.

40 2. A water purifying apparatus comprising a reservoir having an outlet, means for varying the outflow from said reservoir, means for feeding water to said reservoir, a tilting chemical feed box having an outlet, means 45 connected to the chemical feed box and controlled by the volume of water in said reservoir for variably tilting said chemical feed box and automatically varying the outflow of chemical from said feed box.

50 3. A water purifying apparatus comprising a reservoir having an outlet, means for feeding water to said reservoir, a tilting chemical feed box having an outlet, means for adjusting the size of said feed box outlet, 55 means connected to the chemical feed box and controlled by the volume of water in said reservoir for variably tilting said chemical feed box and automatically varying the outflow of chemical from said feed box.

60 4. A water purifying apparatus comprising a reservoir having an outlet, means for varying the outflow from said reservoir, means for feeding water to said reservoir, a tilting chemical feed box having an outlet, 65 means for adjusting the size of said feed box

outlet, means connected to the chemical feed box and controlled by the volume of water in said reservoir for variably tilting said chemical feed box and automatically varying the outflow of chemical from said feed box. 70

5. A water purifying apparatus comprising a reservoir, a discharge therefrom, variable according to the volume of water therein, a water supply thereto, a chemical supply, a tilting chemical box having a vertical slot 75 therein, and connections to move said box to vary automatically the outflow of chemical from said box according to the supply of water in said reservoir.

6. A water purifying apparatus comprising a reservoir, a water supply thereto, a chemical supply, a movable chemical box, said box having a vertical slot, devices connected with said box and arranged to be controlled by the supply of water in the reservoir for automatically varying the output of chemical from said box, and a return pipe adjacent said box arranged to receive the excess of chemical. 80

7. A water purifying apparatus comprising a reservoir, having a variable discharge, a water supply thereto, a chemical supply, a tilting chemical box having vertical slots 90 therein at its opposite ends, one of said slots being adapted to deliver into the outflow of 95 said reservoir, and the other to a return pipe, and connections for tilting said box variably according to the volume of water in said reservoir.

8. A water purifying apparatus comprising a reservoir, a vertical discharge slot 100 therein, a water supply thereto, a chemical supply, a tilting chemical box, vertical slots 105 therein at the opposite ends, one of said slots being arranged to deliver into the outflow of the reservoir, means for adjusting the width of said latter slot and connections for variably tilting said box according to the volume of water in the reservoir.

9. A water purifying apparatus comprising a reservoir, a variable discharge therefrom, a water supply thereto, a chemical supply, a tilting chemical box, having a variable discharge, a float in said reservoir and connections between said float and said chemical 110 box to automatically move the latter so as to discharge variable quantities of chemical according to the position of said float. 115

10. A water purifying apparatus comprising a reservoir, a water supply thereto, a chemical supply, a tilting chemical box, having vertical slots at its opposite ends, one of said slots being arranged to discharge into the outflow of said reservoir and the other into a return pipe, a float in said reservoir and connections from said float to said box whereby the latter will be tilted variably according to the position of the float. 120

11. A water purifying apparatus comprising a reservoir, a vertical discharge slot 125 130

therein, a water supply thereto, a chemical supply, a tilting chemical box having vertical slots in its opposite ends, one of said slots being adjustable and arranged to empty into the outflow of said reservoir, a return pipe arranged to receive the discharge from the other of said slots, a float guided in said reservoir, a pivoted lever connected to said float and to said box and arranged to tilt the box variably according to the vertical position of the float.

12. A water purifying apparatus comprising a reservoir, having a variable discharge, a water supply thereto, a chemical supply, a tilting chemical box having openings therein at its opposite ends, one of said openings being adapted to deliver into the outflow of said reservoir and the other to a return pipe, and connections for tilting said holder variably according to the volume of water in said mixing box.

13. A water purifying apparatus comprising a reservoir, a vertical discharge slot therein, a water supply thereto a chemical supply, a tilting chemical box, openings therein at the opposite ends, one of said openings being arranged to deliver into the outflow of said reservoir, means for adjusting the width of one of said openings and connections for variably tilting said box to the volume of water in the reservoir.

14. A water purifying apparatus comprising a reservoir, a water supply thereto, a chemical supply, a tilting chemical box, having openings at its opposite ends, one of said openings being arranged to discharge into the outflow of said reservoir, and the other into a return pipe, a float in said reservoir, and connections from said float to said box whereby the latter will be tilted variably according to the position of the float.

15. A water purifying apparatus comprising a reservoir, a vertical discharge slot therein, a water supply thereto, a chemical supply, a tilting chemical box having openings in its opposite ends, one of said openings being adjustable and arranged to empty into the outflow of said reservoir, a return pipe arranged to receive the discharge from the other of said openings, a float guided in said reservoir, a pivoted lever connected to said float and to said box and arranged to tilt the box variably according to the vertical position of the float.

16. A water softening apparatus including a tilting container for chemical having a discharge opening for permitting the passage of the chemical into the water, and mechanism automatically operated by the water for causing the level of the chemical to occupy varying positions relatively with respect to the discharge opening to alter the quantity of chemical supplied to the water as the quantity of water supplied for treatment varies.

17. A water softening apparatus including a tilting container for chemical having a discharge opening for permitting the passage of chemical into the water, and mechanism automatically operated by the water for regulating the position of the container to thereby adjust the level of the chemical with respect to the discharge opening to vary the quantity of chemical supplied to the water as the quantity of water supplied for treatment varies.

18. A water softening apparatus including a tilting container for chemical having a discharge opening for permitting the passage of chemical into the water, and mechanism automatically operated by the water for regulating the level of the chemical with respect to the discharge opening to vary the quantity of chemical supplied to the water as the quantity of water supplied for treatment varies, said mechanism including a float supported by the water and having operative connection with said container.

19. A water softening apparatus including a tilting container for chemical having a discharge opening for permitting the passage of chemical into the water, and mechanism automatically operated by the water for regulating the position of the container to thereby adjust the level of the chemical with respect to the discharge opening to vary the quantity of chemical supplied to the water as the quantity of water supplied for treatment varies, said mechanism including a float supported by the water and having operative connection with said container.

20. A water softening apparatus including a tilting liquid container having a discharge opening for permitting the passage of liquid from the container, and mechanism automatically operated by the water provided for treatment for causing the level of the liquid to occupy varying positions relatively with respect to the discharge opening to alter the quantity of liquid discharged from the container as the quantity of water supplied for treatment varies.

21. A water softening apparatus including a tilting liquid container having a discharge opening for permitting the passage of liquid from the container, and mechanism automatically operated by the water provided for treatment for regulating the position of the container to thereby adjust the level of the liquid within the container relatively with respect to the discharge opening to alter the quantity of liquid discharged from the container as the quantity of water supplied for treatment varies.

22. A water softening apparatus including a tilting liquid container having a discharge opening for permitting the passage of liquid from the container, and mechanism automatically operated by the water provided for

treatment for regulating the position of the discharge opening to thereby adjust the level of the liquid within the container relatively with respect to the discharge opening to alter 5 the quantity of liquid discharged from the container as the quantity of water supplied for treatment varies.

In testimony whereof I affix my signature in presence of two witnesses.
